UNITED STATES PATENT OFFICE.

LOUIS A. ETCHISON, OF CANA, NORTH CAROLINA, ASSIGNOR OF ONE-HALF TO JOHN RAY EATON, OF CANA, NORTH CAROLINA.

GRAIN-CLEANING MACHINE.

1,117,822.

Specification of Letters Patent. Patented Nov. 17, 1914.

Application filed October 2, 1911. Serial No. 552,293.

To all whom it may concern:

Be it known that I, LOUIS A. ETCHISON, a citizen of the United States, residing at Cana, in the county of Davie, State of North Carolina, have invented certain new and useful Improvements in Grain-Cleaning Machines; and I do hereby declare the following to be a full, clear, and exact description of the invention, such as will enable others skilled in the art to which it appertains to make and use the same.

This invention relates to new and useful improvements in grain cleaning machines.

The principal object of this invention is the provision of an apparatus of the nature described, which will not only remove all foreign substances from the grain, but which also separate the grain into different grades according to their size.

A second object of this invention is the provision of a grain cleaning machine which employs the use of a hopper provided with a gate and a plurality of hinged closing plates which are operated at different times to open and close the discharge chute and equally distribute the grain contained therein over a space equal to the length of the hopper.

Another object of this invention is the provision of a grain cleaning machine in which are embodied a pair of riddles, one of which is spaced above the other and between which the grain passes, and a fan, the air from which, is directed between the riddles for the purpose of blowing the light grains and other foreign substances from the remainder of the grain in its passage between said riddles.

Still another object of this invention is the provision of a device of the nature specified, in which the passage of the grain is controlled by a suitable plate which can be swung to direct the grain from the apparatus or into engagement with mechanism for further cleaning the same.

A fifth object of this invention is the production of a grain cleaning apparatus in which is provided means for removing the onions from the grain.

A further object of this invention is the construction of an apparatus of the class described in which is located mechanism for removing the cockle from the grain.

A still further object of this invention is

to improve devices of this character rendering them comparatively simple and inexpensive to manufacture, reliable and efficient in use and readily operated.

With the above and other objects in view this invention resides in the novel features of construction, combinations, formations and arrangements of parts to be herein-after more particularly described, claimed and illustrated in the accompanying drawings, in which,

Figure 1 is an elevation of my invention looking at one side thereof. Fig. 2 is a similar view looking from the opposite side. Fig. 3 is a top plan view thereof. Fig. 4 is an end view looking from one direction. Fig. 5 is a similar view looking from an opposite direction. Fig. 6 is a longitudinal sectional view taken on the line 6-6 of Fig. 3. Fig. 7 is a transverse sectional view taken on the line 7-7 of Fig. 1. Fig. 8 is a horizontal sectional view taken on the line 8-8 of Fig. 1, and Fig. 9 is a similar view taken on the line 9-9 of Fig. 1.

Referring to the accompanying drawings by similar characters throughout the several views, the numeral 10 designates generally my improved apparatus which consists of a frame 11 comprising opposite corner posts 12 and 13 of different types which posts are connected by intermediate cross beams 14 which extend longitudinally of the frame and transversely extending beams or bars 15 which connect the lower ends of the upright and provide a means for supporting the same. The upper ends of the uprights 12 and 13 are connected by inclined cross bars 16 while to the inner sides of the said uprights and longitudinally extending bars are secured side plates 17 between which are mounted the various elements for cleaning the grain. The upper ends of the plates 17 are extended above the inclined bars 16 and support thereon the side rails 18 of a hopper 19. This hopper 19 consists of V shaped end plates 20 connected at their opposite edges by downwardly converging side plates 21.

A shaft 22 is journaled in suitable bearings 23 secured to the upper edges of the inclined bars 16 adjacent the extensions of the side plates 17 and has keyed thereto a plurality of blades 24 which produce a blow fan 25. A casing 26 surrounds the fan 25

and is secured at its opposite ends to the ends of the said extensions of the side plates 17.

The rear ends of the hopper 19 has formed thereon and extending rearwardly therefrom a pair of apertured ears 27 in which is journaled a shaft 28. This shaft 28 pivotally supports upon the hopper a plurality of closing plates 29 the terminals of which are arranged to close the slot 30 formed between the downwardly converging plates 21 while the opposite ends are curved outwardly from the hopper for engagement with a plurality of pins 31 extending in staggered relation from a shaft 32 journaled in the side plates 17. This shaft 32 has keyed thereon upon the outside of the plates 17 a pulley 33 by means of which the said shaft is rotated. A baffle plate 34 is arranged below the said hopper 19 and serves to direct the grain in its passage therefrom upon the upper of a pair of riddles 35 and 36 supported by a frame 37. This frame 37 consists of a pair of opposite side plates 38 connected at their lower edges by a base plate 39 which terminates in spaced relation from the rear ends thereof and at their rear extremities by a connecting bar 40 and connecting rod 41 one end of the riddle 35 rests upon the rod 41 while the opposite end is provided with a pair of trunnions 42 engaged within grooves 43 formed in the upper edges of the side plates 38. The frame 37 is connected to the side plates 17 by a pair of arms 44 pivoted to the side plates 17 and plates 38 respectively, while in order to transmit an oscillatory movement to the frame 37 and riddles 35 and 36 respectively, the said frame has pivoted to the opposite sides thereof a pair of pitmen 45 which engage at their outer ends eccentrics 46 keyed to the before described fan shaft 22. A plate 47 is secured to the lower side of the riddle 35 and serves to direct the grain upon the upper or rear ends of the riddle 36. A pair of chutes 50 and 51 are arranged below the riddle 36 and have their opposite inclined sides projecting beyond the terminals thereof as clearly illustrated in the longitudinal sectional view designated by Fig. 6 of the drawings. The chute 50 is adapted to receive such grain as will pass through the openings in the upper portion of the screen 52 of the riddle 36, while a plate 53 is secured to the underside of the lower half of such riddle and is adapted to direct into the chute 51 such grain as will pass through the openings in the lower portion of the screen of the riddle 36. It should be noted that only the heavy material will fall through the openings while all foreign substances of a lighter nature together with a quantity of the smaller grain will pass over the end of the riddle 36 and fall parallel to a vertical plate 54 secured to the inner

faces of the opposite side plates 17 by suitable spring clips 55.

The upper of the rails has located thereon bearing 55 in which is journaled a shaft 57 arranged in spaced parallel relation from the lower end of the plate 54. This shaft 57 has secured thereto a plurality of hubs 58 from which extend radial arms 59 the opposite terminals of which are apertured as at 60 to provide a means of attaching thereto a sleeve 61. This sleeve 61 is provided at its opposite ends with circumscribing flanges 62 between which are located a plurality of loosely mounted rings 63 the peripheries of which are serrated as at 64 to produce a plurality of teeth which co-act with the plate 54 and serve to engage the onions mixed with the grain and remove the same therefrom. A shaft 65 is journaled in spaced parallel relation to the shaft 57 in suitable bearings 66 and has keyed thereon a brush 68 the bristles 69 of which engage the serrations 64 and remove the onions therefrom causing them to fall upon a forwardly inclined plate 70 from whence they will be directed to the exterior of the machine and into a suitable receptacle not shown in drawings.

The front wall of the chute 51 which is designated by the numeral 71 terminates a distance below the upper edge of the opposite wall 72 the upper terminal of the wall 71 has hinged thereto an extension 73 which may be turned either to engage the plate 54 or the end of the plate 53 thereby directing the grain either into the said chute 51 or into a chute 74 formed by a pair of downwardly converging plates 75 and 76 the former of which is secured to the upper edge of the plate 70 while the latter is secured to the plate 71 adjacent its pivotal connection with the plate 73 the lower edges of the plates 75 and 76 are spaced apart to produce a slot 77 through which the contents of the chute 74 are directed between a pair of rollers 78 and 79 keyed to shafts 80 and 81 journaled at their opposite ends in suitable bearings 82 secured to the upper edges of the brace bars 14 located above the transverse bars 15.

A double hopper 83 is located below the rollers 78 and 79 and comprises a plurality of downwardly converging plates 84 and 85. The upper ends of the outer of the plates 84 and 85 are secured one beneath the shaft 80 which supports the roller 78 and the opposite to a point in advance of brush 86 keyed upon a shaft 87 journaled in suitable bearings 88 secured to the upper edges of the bars 14 adjacent the uprights 12. The upper ends of the plates 84 and 85 located at the inner sides of the said double hopper terminate below the shaft which supports the roller 79 at which point they are secured together producing two inclined surfaces 130

faces which direct the contents thereof through the discharge openings formed in their bottoms.

The rollers 78 and 79 are provided with flexible coverings 88 and 89 which serve to prevent any injury to the grain while passing therethrough while the last mentioned covering is of such nature that the cockle contained within the grain will adhere thereto and upon the rotation of the said roller will be scraped therefrom by the previously mentioned brush 86. A baffle 90 is hinged at the meeting ends of the inner plates 84 and 85 and may be moved to project into either of the compartments 91 and 92 located between the said inner and outer plates 84 and 85. A stub shaft 93 is journaled in a suitable bearing 94 attached to one of the uprights 13 and has keyed to its outer extremity a pulley 95. A cable 96 passes over this pulley and over a similar pulley 97 of less diameter keyed to the terminal of the shaft 22 whereby power is transmitted to the fan. The before mentioned pulley 33 frictionally engages the belt 96 and imparts a rotary movement to the shaft 32 thereby providing a means for operating the plates 29. The shaft 80 which supports the roller 78 has keyed thereon a pulley 98 which is connected to the shaft 22 through the medium of a belt 99 and pulley 100 keyed to the said last mentioned shaft. The shaft 80 which supports the roller 78 has further keyed thereon a gear wheel 101 which meshes with a similar gear wheel 102 keyed to the shaft 80 which supports the roller 79. The opposite end of this last mentioned shaft has keyed to its opposite end a pulley 103 over which passes a cable 104. This cable 104 also passes over pulleys 105, 106 and 107 keyed to the adjacent ends of the shafts 55, 65 and 87 respectively which serve to impart the proper rotary movement to the said shafts and the operating means connected thereto.

From the foregoing disclosures taken in connection with the accompanying drawings it will be manifest that a grain cleaning apparatus of the nature described is produced which will fulfil all of the necessary requirements of such a device.

Having thus fully described this invention what I claim is new and desire to protect by Letters Patent is:

1. In an apparatus of the class described, the combination with means for separating relatively large particles of foreign matter from the grain, and means located below the first mentioned means for separating the relatively smaller particles from the grain, of a hopper and a chute located between the two separating means and diverging relatively to each other, the hopper conducting the grain and smaller particles of foreign matter and the chute conducting the separated particles of larger foreign matter away from the first separating means.

2. In an apparatus of the class described, the combination with two distinct separating means spaced apart and located one above the other, of a hopper and a chute located between the two separating means, the upper end of the chute meeting the upper end of the hopper, said chute and hopper diverging relatively to each other.

3. In a grain separator, the combination with a frame, of a vertically disposed plate mounted within the frame, a roller mounted adjacent said plate and provided with a plurality of peripherally arranged toothed rings adapted to coöperate with the plate in the revolution of the roller to remove foreign substances from the grain passing said plate, a depending hopper located below the plate and roller, and adapted to have the grain pass therethrough, a chute located below the roller with its upper end meeting the upper end of the hopper, said chute extending in an opposite direction from the hopper and designed to convey foreign substances from the roller, and a pair of rollers mounted below the hopper, one of said rollers having a covering designed to remove any foreign substance which may remain in the grain passing through the hopper.

In testimony whereof, I affix my signature, in presence of two witnesses.

LOUIS A. ETCHEISON.
